UNITED STATES PATENT OFFICE

IRWIN W. DAVID, OF NEW YORK, N. Y.

FOOTWEAR AND METHOD OF MAKING THE SAME

Application filed September 30, 1930. Serial No. 485,375.

This invention relates to an improvement in footwear and the method of making the same and in particular to a shoe or sandal, and the method by which it is made, of any type ordinarily worn by men, women or children.

It is a feature of this invention that the shoe or sandal and the method of its manufacture, is greatly simplified as compared with previous practise. The shoe or sandal produced by my improved method is characterized by greatly increased flexibility and comfort, especially in the ball part, to a degree not attainable with the ordinary turned or outsole-stitched shoe, and at the same time the heel portion is so formed as to take advantage of the strengthening and shaping effect of the presence of a counter within the quarter of the shoe.

A further feature of the invention is to provide a one-piece sole member extending throughout the shoe and furnishing adequate means of attachment for all upper parts of the shoe without the necessity for the introduction of additional portions such as insoles and the like for attachment of the upper, quarter and the like. Thus I have found it possible to do away entirely with machines whose function it is to stitch or nail the upper and the quarter to the insole and in the practise of my improved process of shoe construction I have been able to build a shoe more rapidly, more cheaply and more strongly than any heretofore known of the same general type and appearance.

It is a further feature of the invention to provide a shoe, and a method of making it, in which the quarter and counter may be attached and held in place without the use of any welt or McKay stitching and without the necessity for skiving or splitting the edges of the sole. It is thus possible to form a stronger shoe than one in which the leather has been weakened by lateral skiving or by McKay stitching.

It is a further feature of the invention to provide a shoe, and a method for its manufacture, having but a single sole piece or member but which nevertheless may be equipped at the shank region thereof with a

strengthening shank of stiff fibrous material or the equivalent which is wholly concealed from view, which is cushioned from the foot of the wearer and in no way interferes with the stitches or nails which secure the counter and quarter to the sole piece.

A further object of the invention is to provide a shoe, and a method for its manufacture, in which there is no outsole stitching whatever but which nevertheless in its heel portion is provided with a molded and shaped quarter inturned at the bottom apparently secured to a sole whose edge can be seen, but which in fact is not stitched or sewed at any point.

Further features, objects and advantages of the invention will appear in connection with the following description.

This application is a continuation in part, and the invention herein described and claimed is an improvement upon, the invention of my pending application for an "Improvement in footwear" Serial No. 469,046, filed July 19, 1930.

In the annexed drawings which form a part of this specification

Fig. 1 is a perspective view of the sole piece of my improved shoe, molded and split for the subsequent operation. The sole piece is shown in its inverted or upside-down position.

Fig. 2 is a perspective view showing the sole piece of Fig. 1 after attachment thereto of the quarter, counter and lining, and a heel stiffening member.

Fig. 3 is a perspective view showing the assembly of Fig. 2 after insertion therein of the supporting shank.

Fig. 4 is a perspective view showing the assembly of Fig. 3 after the lower portion of the sole has been put in place to cover the shank.

Fig. 5 shows in perspective the complete shoe made according to my invention after attachment of the upper in the forepart, the heel lift, the straps, etc.

Fig. 6 is a vertical cross-section through the longitudinal axis of the shoe shown in Fig. 5.

Like reference numerals indicate like parts in the several figures.

Referring to the drawings, I first form a molded sole piece 10 of stout sole leather having an upturned marginal flange 11 defining the edge thereof in the fore or ball part of the shoe. The marginal flange 11 is punched by openings 12 through which the upper may be attached. For convenience I describe and show herein a shoe having an upper woven from leather strands. It will be understood that uppers of any known type may be attached to the upturned flange 11 in any known way, either with or without the previous punching of the holes 12.

From the region of the line 13, 13 and rearwardly thereof (which line 13, 13 designates approximately the rearward end of the portion of the sole piece which bears upon the ground when the shoe is in use) the sole piece is suitably narrowed and is horizontally split across the full width thereof to form a lower or outer flap 14 and an upper or inner flap 15. The line of cleavage between the upper and lower flaps is indicated by dotted lines 16 in Fig. 1 and lies approximately in the region of the line 13, 13 or slightly forward thereof.

The rearward end of the flap 14 is for convenience trimmed to the shape shown at 17 in Fig. 2; and is skived to about half the thickness of the portions of flap 14 forwardly thereof, for convenient attachment of the heel lift, and its edges suitably tapered.

The quarter 18 with a suitable counter 19 and lining 20 is then bent around the inner flap 15 of the sole piece and nailed or otherwise secured in place as indicated by nails 21 in Fig. 2. I prefer to insert a heel stiffening member 22 underneath the flap 15 and between it and the inturned flanges of the lining 20. This may conveniently be made of stiff fibrous material through which nails can be driven and it serves to give strength to the heel portion of the shoe where the weight of the foot rests. It will be noted that it occupies a position between the upper and lower flaps of the sole piece when the shoe is entirely assembled.

There is next inserted over the inturned edges of the quarter, counter and lining a suitable shank piece or strengthening member 23, as indicated in Fig. 3. This is preferably formed of stiff fibrous material so that

it may be stitched in place by the stitches 24, which bind it tightly to the inner flap 15 of the sole piece and cause it to grip tightly the inturned margins of the quarter, counter and lining, and thus form a strong unitary heel structure. The shank piece is of sufficient length to extend forwardly from the heel through the shank region of the shoe to a line 26 at or close to the line of cleavage 16 between the upper flap 15 and the lower flap

14 of the sole piece 10. This is in the neighbor-

hood of the line 13, 13 as best illustrated in Fig. 3. The shank piece is sufficiently held in place at its forward end 26 by the upper and lower flaps of the sole piece 10 and need not be stitched at or near that point.

The lower flap 14 of the sole piece 10 may now be firmly pressed in contact with the unitary heel structure and secured in this position, as shown in Fig. 4, by suitable adhesive. The heel lift 25 is then attached, preferably by nailing, in such a way as to secure the flap 17 between the heel lift 25 and the unitary heel structure and thus to unite the whole permanently.

A suitable upper may be attached to the forepart of the shoe, together with straps, buckles and the like and, if desired, a sock lining (not shown) may be inserted.

The shoe thus described has all the advantages of shoes heretofore known, and in addition has the particular merit that but a single piece of sole leather is required for each shoe, and this forms with the upper in the heel portion a satisfactory shoe in which there are no stitches whatever passing through the outer or lower flap 14. There is thus no necessity for any welt or McKay stitching to hold the lower or outer flap of the sole in place throughout the shank region of the shoe. The stitching required is wholly confined to that

which is necessary to secure the shank piece 23 in place and this, in turn, is a simple stitching operation in the central portion of the shoe which does not require complicated machinery or the lateral splitting of the leather at the edges thereof with subsequent restoring and pasting the marginal flap (as required with McKay stitching operations). It is a particular advantage of my shoe that the heel lift serves as a means of holding in place the lower or protecting flap of the main sole piece while the heel structure and the inner flap of the main sole piece are secured in a strong unitary structure by means of the stitches passing through the shank and the inner flap of the sole. The shank piece thus is hidden from view and cannot break through to injure the stocking or make the shoe uncomfortable. Moreover, considering the shoe structure here disclosed as a whole, it is obvious that the shoe does not require in its manufacture the use of any welt or outsole stitching machines, and that the sole member in the forepart of the shoe is a single stout piece of leather nowhere pierced for stitching purposes (except in its upturned margins) and therefore water-proof to a degree not attainable in ordinary kinds of shoes. It will also be noted, that because of the upstanding marginal flanges defining the edges of the forepart of the shoe a degree of flexibility and expansibility with the foot is provided which cannot be found in the ordinary forms of shoe. This leads to greatly increased comfort. At the same time, a stylish

trim appearance is not sacrificed for comfort, for by means of my construction I am enabled to combine a stiff and molded heel structure, where comfort does not demand expansibility, with a forepart which is expandable with the foot, all being combined in a shoe which requires no outsole stitching, eliminates the necessity for using an inner sole, and is suitably strengthened by a concealed shank at its arch portion.

The process or method of making my shoe is simple and inexpensive. The sole piece is cut to an appropriate shape and the edges in the forepart are molded upwardly under pressure while the leather is moist to form a suitable marginal flange. Holes for the suitable attachment of the upper in the forepart may be punched either then or after the heel structure has been assembled. At the same time the sole piece is split entirely across from the rear end to approximately the forward end of the arch portion. The shoe is then assembled as herein disclosed. The quarter, counter and lining are first bent upon the upper flap of the sole in the heel region and stitched or nailed in place. The shank is then stitched in place in such a way as to secure itself, the inturned edges of the quarter, counter and lining, and the inner flap of the sole piece, in one unitary structure. The heel lift is then applied to hold the lower or outer flap of the sole piece in position to conceal the stitching through the shank. At no stage is it necessary to provide or employ an insole, nor to employ the stitching operations necessary in connection with an insole. The shoe is therefore less expensive to manufacture because the main sole piece is made to perform the functions both of an in- and an out-sole, and in addition all outsole stitchings are eliminated.

Where the expression "heel upper assembly" is used in the appended claims, it will be understood to include the quarter 18, counter 19 and lining 20, or any one or more of these, with or without the addition of other similar elements, constituting the upper part of the shoe in the shank and heel region.

I claim:—

1. A shoe comprising a sole formed of a single piece of stock split behind the ball into two sections, these being an inner and an outer section, a heel upper assembly whose lower flanges are inturned below said inner section, a shank-piece of stiff material positioned between said inner and outer sections of the sole and in contact with the inturned flanges of said heel upper assembly, stitches passing through the inner section of said sole and said shank-piece to engage the same tightly upon said inturned flanges and to cause said flanges, said inner section and said shank-piece to form a unitary heel structure, and a heel nailed to said unitary structure in such man-

ner as to enclose between itself and said heel structure the outer section of said sole.

2. A shoe comprising a sole formed of a single piece of stock which in its forepart has upturned marginal edges forming a substantial part of the side of the shoe and perforated near the upper edge thereof for the attachment of an upper and which rearwardly of the ball is split into two sections, these being an inner and an outer section, a heel upper assembly whose lower flanges are inturned below said inner section, a shank-piece of stiff material positioned between said inner and outer sections of the sole and in contact with the inturned flanges of said heel upper assembly, stitches passing through the inner section of said sole and said shank-piece to engage the same tightly upon said inturned flanges and to cause said flanges, said inner section and said shank-piece to form a unitary heel structure, and a heel nailed to said unitary structure in such manner as to enclose between itself and said heel structure the outer section of said sole.

3. The method of making a shoe containing a sole composed of a single piece of stock and split into two sections behind the ball, these being an inner and an outer section, said method comprising laying the inturned flanges of a heel upper assembly upon the inner section of said sole so as to embrace the same, laying a strip of shank-stiffening material upon said inturned flanges so as to cover at least a portion of the same, attaching said strip and said inner section in such manner as to engage the same tightly upon said inturned flanges and to cause said flanges, said inner section and said shank-piece to form a unitary heel structure, laying the outer section of said sole upon said unitary structure without stitching the same thereto, and nailing a heel upon said outer section and said unitary structure in such manner as to enclose the said outer section of the sole between said structure and said heel.

4. An unturned shoe comprising a sole whose forepart is vertically upturned around the margin of the shoe to form a portion of the wall of the shoe at the front and sides of the forepart thereof, and which rearwardly of the ball is split into two sections, these being an inner and an outer section, a heel upper assembly secured to said inner section in such manner as to form a unitary heel assembly therewith, and a heel, said outer section of the sole being secured without stitching between said heel assembly and said heel.

In testimony whereof, I have signed my name to this specification.

IRWIN W. DAVID. 125
